(57) **CLAIM**

We claim the ornamental design for a faucet and soap dispenser set, as shown and described.

DESCRIPTION

FIG. 1 is a front, right, perspective view of the claimed design;

FIG. 2 is a front side view thereof;

FIG. 3 is a rear side view thereof;

FIG. 4 is a right side view thereof;

FIG. 5 is a left side view thereof; and,

FIG. 6 is a top view thereof.

The broken lines in the drawings depict portions of the faucet and soap dispenser set and the environmental structure that form no part of the claimed design. Bottom views of each embodiment have been omitted due to the disclaimed sink (e.g., basin, receptacle, etc.) blocking or substantially blocking the view of the ornamental features of the claimed design.
